REINFORCED CENTRAL TUNNEL FOR
X-MEMBER OF CHASSIS FRAMEWerner G. Hess, Dearborn, Mich., assignor to The
Murray Corporation of America, Detroit, Mich.,
a corporation of Delaware

Application September 7, 1950, Serial No. 183,490

10 Claims. (Cl. 280—106)

1

This invention relates to vehicle chassis frames and more particularly to improvements in the X-framing members of vehicle chassis frames.

One of the objects of this invention is to provide a simple but extremely rigid union or connection between the arms of the X-member which will successfully resist weaving or twisting of the X-member and consequently the chassis frame, in any and all directions.

Another object of this invention is to provide, in an X-member composed of two opposed substantially V-shaped elements, a union or connection therebetween which acts substantially as a continuing connection between the aligned arms of the opposed V-shaped elements of the X-member while leaving an opening therein through which a propeller shaft may extend.

Still another object of this invention is to provide an X-member in which the union or connection between the elements of the X-member includes a quasi tubular structure having as inherent characteristics the ability to resist both bending and twisting strains and stresses.

Various other objects, advantages, and novel details of construction of this invention will become more apparent as this description proceeds, especially when considered in connection with the accompanying drawing in which:

Fig. 1 is a fragmentary top plan view of a vehicle chassis frame provided with an X-member constructed in accordance with this invention;

Fig. 2 is a view in side elevation of the structure shown in Fig. 1;

Fig. 3 is an enlarged top plan view of the union or connection between the V-shaped elements of the X-member;

Fig. 4 is a vertical sectional view of the structure illustrated in Fig. 1 taken on the line 4—4 thereof;

Fig. 5 is a vertical sectional view of the structure illustrated in Fig. 1 taken on the line 5—5 thereof; and

Fig. 6 is a plan view of the cylindrical member of the chassis frame through which the propeller shaft operates.

In the drawing the reference character 10 indicates the longitudinal side members of the vehicle chassis frame only one however being illustrated. These members 10 are shown as channel shaped with the channels facing inwardly.

The X-framing members are disposed between the side members 10 and each comprises a pair of substantially V-shaped elements 11, here shown as channel shaped in cross section, ter-

minally connected as at 11a by rivets or other suitable means to the inside of the channel of the members 10 as shown. The V-shape elements 11 are assembled with the opposite arms of the pair of elements in substantial alignment and apices of the V's spaced apart. Each pair of elements 11 is connected by a union or connection indicated generally by the reference character 12.

This union or connection 12, which forms the particular subject matter of this invention is in the form of a box-like or so-called "dog house" structure and consists in part of an upper or top gusset plate member 13 and a lower or bottom gusset plate member 14, riveted or otherwise rigidly secured as at 15 to the flanges of the V-shaped elements 11 at the apices thereof.

The top gusset plate 13 is formed with an upwardly extending or crown portion 16 and its opposite ends are cut away as at 17 and are provided with downwardly extending flanges 18. The lower gusset plate 14 is shown as being flat.

Disposed within the box-like structure defined by the gusset plates 13 and 14 and the adjacent apices of the elements 11 is a pair of inner reinforcing members or elements 19. These members 19 are substantially semicylindrical in vertical cross-section and are assembled and secured together with their concavities facing one another to produce or form a quasi tubular structure which provides an opening 20 through which a propeller shaft may extend.

The opposed edges of the elements 19 meet and engage one another longitudinally intermediate their ends both at the top and bottom thereof and at this area the cross-sectional shape of the assembled pair of elements 19 is truly tubular.

The elements 19 decrease in depth from their area of abutment toward their ends as will be apparent from an examination of Figs. 3, 4 and 5. Thus the elements 19 form arched channels decreasing in depth from their longitudinal centers toward their ends and the bases of these channels are in substantial alignment with and act substantially as connections between and continuations of, the aligned arms of the opposed V-shaped elements 11 of the X-member.

The top and bottom edges of the elements 19 are provided with flanges 21 and in the area of abutment these flanges extend into slots in the top and bottom gusset plates 13 and 14 and are welded or otherwise rigidly attached thereto as indicated at 22. These flanges 21 diverge from the welds 22 in X-relationship substantially in alignment with the legs of the X-forming members 11. The flanges at the top engage down-

wardly extending flanges 18 of the top gusset plate 13 and may be welded or otherwise secured thereto. The flanges 21 of the bottom at points spaced from the welds 22 rest on the bottom gusset plate 14 as shown at the left in Fig. 5. Vertically extending circumferentially arranged reinforcing ribs 23 may be formed in the elements 19 if desired to provide further strength thereto.

With the described structure, which embodies the combination of top and bottom gusset plates with a quasi tubular inner reinforcement, it is possible to produce an X-member which will successfully resist all weaving, twisting, and bending strains and stresses to which the chassis frame is subjected. These stresses which are imparted to the gusset plates by the V-shaped elements of the X-member are transferred to the quasi tubular reinforcing member and resisted thereby. The multiple tapering configuration of the inner reinforcing member provides a substantially continuing connection between the aligned arms of the opposed V-shaped elements of the X-member whereby longitudinal loads imparted to any one of said arms may be transmitted to the other arm in longitudinal alignment therewith. The X-member is light in weight for the amount of strength embodied therein when providing a passage for a propeller shaft.

What is claimed is:

1. In a vehicle chassis frame having longitudinal side members, an X-member therefor comprising a pair of substantially V-shaped elements located between said side members, each said element having a pair of legs secured to opposite side members, and means connecting said V-shaped elements together including plate members rigidly attached to the top and bottom of said V-shaped elements at the apices thereof, a tubular member between said plate members and said elements rigidly connected to the plate members, and continuously extending webs on said tubular member in substantially X-relationship, with each arm of the X substantially aligned with a leg of the V-shaped elements.

2. In a vehicle chassis frame having longitudinal side members, an X-member therefor comprising a pair of substantially V-shaped elements located between said side members with the free ends connected thereto, and means connecting said V-shaped elements together including plate members rigidly attached to the top and bottom of said V-shaped elements at the apices thereof, and two semicylindrical elements forming a tubular member between said plate members rigidly connected thereto, said elements having continuous web portions disposed substantially in X-relationship, with each arm thereof aligned with a leg of the V-shaped elements.

3. In a vehicle chassis frame having longitudinal side members, an X-member therefor comprising a pair of substantially V-shaped elements located between said side members with the free ends attached thereto, gusset plates secured to the upper and lower faces of said V-shaped elements at the apices thereof, a tubular member between said plate members rigidly connected thereto at diametrically opposed points, and flanges extending from said tubular member in substantial alignment with said V-portions of said elements.

4. In a vehicle chassis frame having longitudinal side members, an X-member therefor comprising a pair of elements having angular disposed portions located between said side members with the free ends connected thereto, plate

members rigidly secured to said elements at the junction of the angle portions thereof, a pair of substantially semicylindrical members between said plate members forming a tubular structure, and projections on said last members extending through said plate members and rigidly secured thereto.

5. In a vehicle chassis frame having longitudinal side members, an X-member therefor comprising a pair of elements having angular disposed portions located between said side members with the free ends connected thereto, plate members rigidly secured to said elements at the junction of the angle portions thereof, a pair of substantially semicylindrical members between said plate members forming a tubular structure, projections on said last members extending through said plate member and rigidly secured thereto, and flanges extending from said last members in substantial alignment with the angular disposed portions of said elements.

6. In a vehicle chassis frame having longitudinal side members, an X-member therefor comprising a pair of elements having angular disposed portions located between said side members with the free ends connected thereto, plate members rigidly secured to said elements at the junction of the angle portions thereof, a pair of substantially semicylindrical members between said plate members forming a tubular structure, projections on said last members extending through said plate members and rigidly secured thereto, flanges extending from said last members in substantial alignment with the angular disposed portions of said elements, and flanges on at least one of said plate members extending over the adjacent flanges of said last members.

7. In a vehicle chassis frame having longitudinal side members, an X-member therefor comprising a pair of substantially V-shaped elements having angularly disposed arm portions located between said side members with the free ends connected thereto, and the apices spaced apart, gusset plates secured to the upper and lower faces of said V-shaped elements at the apices thereof, a pair of substantially semicylindrical members located in the space defined by said gusset plates and the apices of said V-shaped elements, said semicylindrical members abutting intermediate their ends forming a tubular portion and being spaced apart from the area of abutment toward their ends, and means rigidly securing said semicylindrical members within said plate members and elements with the spaced apart portions substantially aligned with the arm portions of said elements.

8. In a vehicle chassis frame having longitudinal side members, an X-member therefor comprising a pair of substantially V-shaped elements located between said side members with the free ends connected thereto, plate members rigidly secured to said V-shaped elements at the apices thereof, forming a tunnel therewith, a tubular member located within said tunnel, and flanges extending from said tubular member disposed in substantial alignment with portions of said elements.

9. In a vehicle chassis frame having longitudinal side members, an X-member therefor comprising, spaced upper and lower plate members, legs joining said plate members to said side members forming a central tunnel, and a cylindrical member disposed in said tunnel and secured therewithin, said cylindrical member having continuous webs disposed in X-relationship between

the plates with each arm thereof joined to one of said legs.

10. In a vehicle chassis frame having longitudinal side members, an X-member therefor comprising, spaced upper and lower plate members, legs joining said plate members to said side members forming a central tunnel, and a cylindrical member disposed in said tunnel and secured therewithin, continuous portions of said cylindrical member being disposed in X-relationship between said plate members, the ends of said continuous portions being joined to said legs.
